TAILPIECE FOR A BANJO

Robert G. Baker, 1121 Elm Tree Road, Rossford, Ohio

Filed May 16, 1960, Ser. No. 60,588

Term of patent 7 years

(Cl. D56—1)

FIG-1-

FIG-2-

FIG-3-

FIG-4-

FIG-5-

FIG-6-

FIGURE 1 is a plan view of a tailpiece for a banjo showing my new design;

FIGURE 2 is a side elevation of the tailpiece of FIGURE 1;

FIGURE 3 is an elevational view of the left or front end of the tailpiece as shown in FIGURE 2;

FIGURE 4 is an elevational view illustrating the right or rear end of the tailpiece;

FIGURE 5 is a plan view like that of FIGURE 1 but with the hinged cover of the string posts swung to open position; and

FIGURE 6 is a section taken on the line 6—6 of FIGURE 5 to bring out more clearly the contour of that portion of the tailpiece.

The broken line showing of a portion of a banjo in FIGS. 1 and 2 is for illustrative purpose only.

I claim:

The ornamental design for a tailpiece for a banjo, substantially as shown and described.
